THERMOSTATIC DAMPER REGULATOR

Application filed October 20, 1930. Serial No. 490,050.

The invention relates to thermostatic regulators for combustion furnaces and consists in the novel construction as hereinafter set forth.

5 In the drawings:

Figure 1 is a longitudinal section through a portion of a furnace chimney flue to which our improved regulator is applied;

Figure 2 is a cross sectional thereof;

10 Figure 3 is a plan view showing the arrangement of the magnetic counter-weight.

With combustion furnaces and particularly those using solid fuel, the most effective regulation is through the so-called check 15 which when open admits cold air directly to the chimney flue and diminishes the draft upon the furnace. Our improved regulator is designed to automatically accomplish the regulation of this check valve through means 20 controlled by the temperature of the chimney flue gases, the detailed construction being as follows:

A is a section of the chimney flue extending from the furnace to the chimney (not shown). 25 Mounted upon this flue section is a lever mechanism including a supporting base B bolted or otherwise secured to the flue as indicated at C. At one end of this base member B is pivotally attached an arm D which 30 in turn is secured to a sheet metal cover plate E for closing a check opening F in the top of the flue A. The member D is connected by a link G with a lever H which is fulcrumed to a link I pivotally attached to the opposite 35 end of the base member B. Between the base member B and the lever H is an expansion chamber J. This is preferably formed of two cupped sheet metal members J' J² having abutting flanges J³ which are soldered, brazed, or otherwise secured to each other to form an air seal. The members J' J² have centrally secured thereto the bearing members K and L, the former being cupped to receive the end 40 of a screw M adjustably secured to the lever H and locked in its positions of adjustment by the nut N. The member L engages a socket bearing in the base member B.

45 With the parts constructed as described, the member J is mounted between the base B and lever H and will be held in a position

above the flue A where it is exposed to the radiant heat from said flue as well as to any heat conducted through the base B and member L thereinto. A certain quantity of air originally at atmospheric pressure and sealed 55 within the chamber will when exposed to the radiant heat of the flue be expanded, bulging outward the walls of the member J and thereby moving the lever H. This through its link connections I and G will communicate movement to the hinged member D which will lift the cover plate E. By properly adjusting the screw M the mechanism may be so set that when the heat of the furnace is below 60 normal, the cover E will completely close the opening F. As soon, however, as the generated heat increases, the hot gases passing through the flue A will communicate heat therethrough which by radiation is communicated to the member J, expanding the air 65 therein. This will move the lever H and will swing open the cover E.

70 As a combustion furnace is very sensitive to a check draft, the opening of the cover E will quickly bring about a change, diminishing the rate of combustion and thus by properly setting the device the heat generated by the furnace will remain substantially constant. In making this initial adjustment it is desirable to counterweight the cover plate 75 E so as to assist in closing the opening F when the member J contracts, we have provided a simple means of weighting the cover E which consists in a magnet O resting on said cover. As the cover E is made of iron or magnetic metal, the magnet O will be drawn thereto with sufficient force to frictionally hold it from sliding when the cover plate is adjusted to different angles. However, the member O may be readily moved 80 manually to different positions on the cover plate until properly adjusted to produce the desired regulation.

85 What we claim as our invention is:

90 1. The combination with a chimney flue having a check draft aperture therein and a hinged cover plate for closing said aperture, of a lever connected to said cover plate, a sealed expandible chamber arranged to be exposed to the radiant heat of said flue and 95 100

- operatively engaging said lever, and an adjustable counter-weight on said cover plate formed of magnetized metal and magnetically held in its position of adjustment during movement of said cover plate.
- 5 2. The combination with a chimney flue having a check draft aperture therein and a hinged cover plate for closing said aperture, of a lever connected to said cover plate, a sealed expandible chamber arranged to be exposed to the radiant heat of said flue and operatively engaging said lever, and means associated with said cover plate for governing the effective actuation of the closure incident to any predetermined temperature in the chimney flue, said means comprising an adjustable magnetized counter weight.
- 10 3. In an automatically controlled damper mechanism having a chimney flue provided with a check draft opening, a closure for said opening, and means connected to said closure for automatically operating the same, said means including an expandible chamber exposed to the radiant heat from said flue and responsive to temperature changes therein, a lever operable by said chamber, a supporting member secured to said flue and provided at one end with means for pivotally mounting said closure, at the other end with means for pivotally mounting said lever and intermediate the aforesaid means with a support for said chamber, and a pivotal connection between said lever and said closure.
- 15 4. In an automatically controlled damper mechanism having a chimney flue provided with a check draft opening, a closure for said opening, a relatively narrow supporting member secured to said flue adjacent said opening, an expandible chamber exposed to the radiant heat from said flue, a lever operable by said chamber, linkage pivotally mounted upon the ends of said supporting member one of the links being secured to said closure the other link pivotally connected to one end of said lever, a socket bearing on said supporting member intermediate said links, a depending bearing member on the bottom of said chamber and adapted to rest in said socket, an adjustment member threaded in said lever, a socket bearing on the top of said chamber adapted to be engaged by said threaded member whereby said chamber is rockably supported intermediate said lever and said supporting member, and a link pivotally connected to the free end of said lever and to the aforesaid link secured to said closure whereby upon expansion or contraction of said chamber the aforesaid lever mechanism will operate to open or close said closure.
- 20 5. In testimony whereof we affix our signatures.
